UNITED STATES PATENT OFFICE.

STANISLAUS KUCHARSKI, OF CHARLOTTENBURG, NEAR BERLIN, GERMANY.

ARRANGEMENT OF CENTERING THE FILM IN THE GATE OF CINEMATOGRAPH PROJECTORS.

Application filed August 31, 1921. Serial No. 497,303.

(GRANTED UNDER THE PROVISIONS OF THE ACT OF MARCH 3, 1921, 41 STAT. L., 1313.)

To all whom it may concern:

Be it known that I, STANISLAUS KUCHARSKI, engineer, a citizen of Germany, residing at Charlottenburg near Berlin, Dernburgstrasse 45, Germany, have invented certain new and useful Improvements in Arrangement of Centering the Film in the Gate of Cinematograph Projectors (for which I have filed applications in Germany 10 December 22, 1919; Great Britain May 27, 1920; Germany July 1, 1920), of which the following is a specification.

The invention relates to means for adjusting the film of cinematograph apparatus in 15 the correct position in the window of the gate. In cinematograph apparatus in which the film is constantly moved forward, it is known on making this adjustment to avoid a displacement of the whole device for 20 feeding the film by imparting to the feed wheel a temporary acceleration until the film has attained the right position in the film window. For this purpose the film feed wheel is provided with a toothed wheel 25 which has one tooth less than a toothed wheel of its driving shaft with which it is connected through a sliding coupling. In the normal working a toothed wheel engaging constantly with both of these toothed 30 wheels rotates about the wheels without rotation about its axle, so that the feed wheels are driven directly from their axles and at the same speed. If the rotating toothed wheel is held fast, it receives through the 35 driving shaft and the feed wheel, a rotation about its axle and transmits the rotation of the shaft with somewhat greater velocity to the feed wheel.

For cinematograph apparatus with Maltese cross feeding motion a device of this kind 40 has not previously been used, because it was generally accepted that the masse formed by the intermediate toothed wheel and its mounting parts, as well as the device for 45 holding this toothed wheel stationary, could not be held in rotation by the Maltese cross without disturbing the whole drive. The present invention depends on the recognition 50 that in many cases it is possible to hold the rotating masses so easily that they will not interfere with the normal working when used in combination with the Maltese cross device.

The arrangement can be so constructed

that the intermediate toothed wheel in the 55 normal working is not engaged with the toothed wheel of the driving shaft and the feeding wheel and is only inserted for the purpose of adjusting the film. Consequently, the intermediate toothed wheel 60 remains at rest in the normal working and only rotates about its axle when the film is being adjusted. A circular rotational movement is, therefore, avoided in this construction and the members of the film adjusting device all concerned in the normal 65 working.

The drawings illustrate several modes of construction according to the invention.

Figs. 1 and 2 show one constructional 70 form in two different views,

Fig. 3 is a view of an other form in the direction of the optical axis of the apparatus towards the source of light, and

Fig. 4 a side view of this form.

Fig. 5 shows particulars of the arrangement of Figs. 3 and 4.

The feed wheel *a* (Figs. 1 and 2) as in known devices is mounted loosely on the driving shaft *b* and is connected therewith only 80 through sliding couplings *c*, comprising friction rings which are pressed between the feed wheel *a* and a disc *d* secured to the shaft *b* and a toothed wheel *e* also secured to this shaft. On the feed wheel *a* there is a 85 toothed wheel *f* which has one tooth less than the opposite toothed wheel *e*.

Adjacent to the toothed wheels *e* and *f* there is a toothed wheel *h* mounted on a pivoted lever *g* the width of the wheel *h* 90 being such that it can engage at the same time with both toothed wheels *e* and *f*. It may in the normal working, be held out of engagement with the toothed wheels *e* and *f* for example by a spring *i* so that the rotation of the driving shaft *b* is transmitted by 95 the friction coupling *c* directly to the feed wheel *a*.

If during the working an adjustment of the film setting in the window is necessary, 100 the wheel *h* is moved from the outside of the apparatus by means of a hand wheel *k*, a lever *l* and a link *m* into gear with the wheels *e* and *f*. The frictional movement is transmitted from the shaft *b* to the feed wheel *a* over the wheels *e*, *h* and *f* instead of 105 by the friction coupling and since the wheel *f* has one tooth less than the wheel *e*, the feed

wheel α receives a smaller acceleration than the shaft δ which advances until the film has taken up its correct position in the window. The hand-wheel k is then released and the spring i brings the wheel α again out of engagement.

In the arrangement according to Figs. 3 to 5 a is the frame of the apparatus and b an axle led through the nave of the frame, 10 said axle being driven by the toothed wheel f , pertaining to the gearing for the optical synchronizing of the moving picture. In feeding the film step by step, for instance a Maltese cross may be substituted for the wheel f . On said spindle is fixedly secured by means of a pin on the one hand the toothed wheel e and on the other hand the disc d . Between both parts (e and d) the shifting roller a is arranged to move freely 20 on the spindle b however under a rather great resistance by way of friction caused by the discs d^1 and d^2 . These latter consist of leather or any other suitable material.

Fixedly secured to the shifting roller is a 25 toothed wheel f , possessing the same number of teeth and being of the same size as the toothed wheel e . On the pin p (Fig. 4) mounted on the frame, a fork is provided, freely rotatable thereon and consisting of 30 two rigidly connected parts g^1 , g^2 and carrying, on both its ends a pair of toothed wheels h^1 , $h^{1\prime}$ and h^2 , $h^{2\prime}$ each. Both parts of each pair of toothed wheels are rigidly connected to each other, and one wheel in 35 each pair is provided with one tooth more than the other.

A lever n provided with a handle n' is freely turnable on a pin q mounted on the frame and the spring o tends to keep this 40 lever in a horizontal position. By means of the connecting rod m the lever n is connected to the fork g^1 , g^2 in such a manner, that through the horizontal position of said lever, the fork is likewise kept in a horizontal position, that is to say in such a way, that 45 neither the pair of toothed wheels h^1 , $h^{1\prime}$ nor the pair h^2 , $h^{2\prime}$ becomes active.

With the arrangement of the lever n and the springs r^1 and r^2 as shown in Fig. 5 the 50 lever n may be more reliably held in horizontal position and thus also that of the fork g^1 , g^2 is warranted in so far as both springs referred to are bearing with considerable force and tension upon the extension s provided on the frame of the apparatus, and that each change of position of the lever n out of its central position must be effected under a certain expenditure of 55 power. In the construction as illustrated in Fig. 4 the central position is somewhat unreliable, since each change from that position will commence with an expenditure of power at zero; it may be effected, however, in a somewhat simpler manner than that 60 shown in Fig. 5.

If the lever n by means of the handle n' is shifted from its horizontal position, then either the pair of toothed wheels h^1 , $h^{1\prime}$ become active or the pair h^2 , $h^{2\prime}$. Now the wheels of each pair differ by a tooth and the 70 run of the shifting roller will be accelerated or slowed down when the pair of wheels becomes operative, in accordance as to whether for instance the wheel h^1 possesses one tooth more or less than the wheel $h^{1\prime}$, so that 75 gradually a correct centering of the picture in the gate and in consequence on the screen, is effected.

It is obvious, that it merely depends on the proper disposition of the toothed wheels h^1 , $h^{1\prime}$ on the one hand and h^2 , $h^{2\prime}$ on the other hand in respect of the ratio of transmission in view of the toothed wheels f , e , so that the action of the one pair of wheels will accelerate the movement of the shifting roller 80 while the action of the other pair will slow it down, in accordance as to whether the picture is displayed too high or too low on the screen.

It is further obvious, that if no use is 85 made of this latter advantage, one pair of toothed wheels h^1 , $h^{1\prime}$ or h^2 , $h^{2\prime}$ would suffice, but that during the working of the apparatus frequent adjustment would become necessary, the one or the other loop of the 90 film would steadily grow shorter and be torn in case of inadvertence by the operator. Such occurrence is entirely avoided owing to the two pair of wheels, on the one hand in that through such arrangement it is rendered possible either to accelerate or to slow 95 down the movement of the shifting roller, on the other hand, and secondly, because in the case of the picture being a little out of its proper position on the screen, only such 100 small error is to be corrected by a proper operation of the described device; but with only one pair of toothed wheels that work in one direction only, the film must be adjusted under circumstances almost by the entire 105 length of a picture.

I claim:

1. In mechanism of the class described, means for adjusting the film in the window, comprising in combination with the intermittently moving feed wheel and the drive shaft for the film, of a normally operative frictional connection between the feed wheel and the driving shaft for the film, and manually operated means for positively connecting the feed wheel with the film drive shaft to cause said wheel and shaft to move at different speeds.

2. In mechanism of the class described, means for adjusting the film in the window, comprising in combination with the intermittently moving feed wheel and the drive shaft for the film, of a normally operative frictional connection between the feed wheel and the driving shaft for the film, and manu- 120 125 130

ally operated means for positively connecting the feed wheel and the film drive shaft to accelerate or retard the movement of the shaft with respect to the feed wheel.

- 5 3. In a device for adjusting film in the window of cinematograph apparatus, the combination with the intermittently moving feed wheel and the film driving shaft, of two wheels of unequal size, connected with the feed wheel and film driving shaft respectively, an intermediate wheel for coupling the first two wheels and means for moving the intermediate wheel into and out of operative position.
- 10 4. In a device for adjusting the film in the window of cinematograph apparatus, the

combination with the intermittently moving feed wheel and the driving shaft for the film, of toothed wheels of unequal diameter connected with the feed wheel and with the 20 driving shaft respectively, and a plurality of pairs of rigidly connected toothed wheels mounted to be alternately engaged with the first named pair, thereby to drive the feed shaft with an accelerated or a retarded motion with respect to the feed wheel.

In testimony whereof I have affixed my signature in presence of two witnesses.

STANISLAUS KUCHARSKI.
